UNITED STATES PATENT OFFICE.

ANDRÉ C. ATTENDU, OF MONTREAL, QUEBEC, CANADA.

FUEL FEED FOR DIESEL-TYPE INTERNAL-COMBUSTION ENGINES.

Application filed February 6, 1920. Serial No. 356,774.

This invention relates to improvements in process of and apparatus for supplying fuel oil to Diesel type internal combustion engines, and the object of the invention is to provide for the feeding of oil from a pressure slightly below the air pressure or slightly below the cylinder pressure if the oil is injected directly.

A further object is to provide an oil feeding and measuring device operating under only a slight difference of pressures between intake and discharge whereby flexibility and freedom from leakage may be obtained and small parts of simple construction employed.

A still further object is to provide a measuring device which is at every stroke prepared to deliver the maximum amount of oil but which may be regulated to deliver any fraction of the oil available for delivery.

A further object is to provide a device which may be easily and inexpensively manufactured and which will not readily get out of order.

The device consists briefly of a small auxiliary reservoir on the engine in which fuel oil is maintained at a constant pressure only slightly below the pressure of the intake air or of the cylinder pressure. One or more pumps are provided in conjunction with the reservoir for feeding oil therefrom into one or more cylinders. On the suction stroke, the pistons of these pumps move to the limit of their travel, so as to draw a full charge. On the force or feeding stroke, the travel of the pistons may be stopped at any desired point to regulate the amount of oil delivered. The oil is forced into the auxiliary reservoir by a suitable pump operating proportionately to the engine speed and arranged to deliver a greater volume of oil per unit of time than can be handled by the feed pumps, the surplus oil escaping from the reservoir through an adjustable relief valve, so that the pressure in the reservoir is maintained uniform.

In the drawings which illustrate the invention;—

Fig. 1 is a cross section on the line 1—1, Figure 2, illustrating one form of device embodying the invention.

Fig. 2 is a view partly in longitudinal section.

Referring more particularly to the draw-

ings, 11 designates a reservoir capable of sustaining very considerable internal pressures and having heads 12, one not shown, and 13 designates a casing enclosing the operating parts of the measuring device and having hand-hole plates 14 giving access thereto. A cam shaft or driving shaft 15 passes through the casing. A pressure pump, designated as a whole by the numeral 16, is provided for supplying fuel oil to the reservoir 11. This pump is preferably operated from the shaft 15 and may for convenience be enclosed in the casing 13. It will be understood, however, that this pump may be entirely separate and located at any suitable point.

The pump 16 comprises a body 17 provided with flanges 18 for attaching it to the casing 13 and having any suitable number of bores 19 which are preferably equal in number to the feed pumps which it supplies and which are all in communication with a supply passage 20 to which the suction pipe 21 connects. The pump pistons 22 are preferably of the solid plunger type and operate on the feeding strokes as valves to close off the bores 19 from the supply passage 20, so that the oil is driven out of the bores through the check valves 23 into the discharge pipe 24 and thence through the check valve 25 into the reservoir 11. The outer end of each piston is preferably provided with a roller 26 running on a cam or eccentric 27 fixed to the shaft 15. A spring 28 is arranged between a suitable abutment 29 at the outer end of each piston and the pump body 17. It will thus be seen that the pistons are positively operated by the cams on the discharge strokes and are operated by the springs on the suction strokes.

The reservoir 11 is provided with an adjustable relief valve 30 of any suitable design having an overflow pipe 31 which leads back to a main oil reservoir or to the suction pipe 21.

One or more feeding and measuring pumps 32 are provided in the reservoir and each comprises a barrel 33 formed integral with the reservoir or suitably connected thereto having inlet ports 34 communicating with the interior of the reservoir. The plunger 35 of each pump projects beyond the lower end of the barrel and is provided with a pair of col-

lars 36 and 37, between which the forked extremity of an operating lever 38 embraces the plunger. The lever 38 is operated by a cam 39 on the shaft 15 to press against the lower collar 37 and operate the plunger on its suction stroke and at the same time compress a spring 40 located between the collar 37 and an adjustable seat 41 provided in the casing 13. The opposite end of the pump is provided 10 with an outwardly opening check valve 42 and communicates with a fuel feed pipe 43 leading to an injector not shown or other means for delivering oil into an engine cylinder. It will thus be seen that feed pumps 15 are positively operated on the suction strokes from the shaft 15 and are operated on the feed strokes by the springs 40.

In order to regulate the length of feed strokes and therefore the amount of oil delivered by each pump, a tapered member 45 is interposed between the reservoir 11 and the collar 36 of each pump. It is obvious that by shifting this regulator to interpose thicker or thinner parts thereof between the collar 36 and the reservoir, the stroke of the plunger may be regulated.

The feed pumps may be of the fitted plunger type shown or obviously may be of the floating plunger type, the construction 30 being immaterial except as regards simplicity of manufacture.

The operation of the device is as follows:— The force pump 16, which is operated by the shaft 15 in suitable proportion to the speed 35 of the engine, delivers fuel oil to the reservoir 11 in excess of the capacity of the feed pumps 32 to withdraw oil from the reservoir, so that there is always a surplus of oil which escapes through the relief valve 30 and is returned 40 to the suction side of the pressure pump. In this way, a fixed pressure is maintained in the reservoir 11, which bears any desired relation to the air supply pressure or to the cylinder pressure of the engine according as the valve 45 30 is adjusted. Preferably, the difference in pressures is not more than fifteen pounds so that the feed pumps 33 are operating under very easy conditions and are not subject to leakage, especially in the check valves 42. 50 As the shaft 15 revolves, the cams 39 oscillate the levers 38 to draw the plungers 35 out of the barrels 33, that is, to operate the plungers during their suction strokes. During the suction strokes, the valves 42 are closed by back 55 pressure, so that a vacuum is drawn in the barrels 33 until the plungers uncover the ports 34, whereupon oil from the reservoir rushes in and completely fills the pump barrels. During the suction strokes, the springs 60 40 have been compressed between the collars 37 and abutments 41, and, when the cams 39 release the levers 38, these springs drive the plungers into the barrels until the collars 36 strike the regulators 45 and plunger movement is thereby stopped. It will thus be seen

that each barrel is completely filled at each suction stroke and that, by adjusting the regulators, the pumps may discharge anything from a drop of oil to the full displacement of each plunger. Owing to the comparatively small difference in pressures in the reservoir 11 and engine cylinder, the feed pumps need not be of very strong construction nor need the springs 40 be very strong. In this way, much wear and tear in the feed 75 and measuring device is eliminated and accuracy thereby obtained.

The apparatus shown in the drawings is designed to feed two cylinders, but obviously a single reservoir may contain pumps for all 80 the cylinders of an engine, although preferably the construction is arranged as illustrated and operates those cylinders which fire consecutively in a four cylinder or six cylinder engine. Preferably the shaft 15 is geared 85 to revolve at half the speed of a four-cycle engine or at the full speed of a two-cycle engine. Obviously for large cylinders which require individual regulations, a separate reservoir 11 may be provided for each cylinder. 90 In a four-cycle six cylinder engine in which the firing order is 1, 5, 3, 6, 2, 4, feed pumps in pairs as illustrated would be connected to the cylinders 1—5; 3—6; 2—4.

Having thus described my invention, what 95 I claim is:—

1. Fuel feeding apparatus for high compression engines comprising an injector line, a fuel chamber, a measuring pump located within said chamber and communicating with the latter and with the injector line to provide for the forcible delivery of fuel from the chamber into said injector line and means for maintaining in said chamber and throughout the injector line a supply of fuel at a constant 100 normal pressure only slightly below the injection air or cylinder pressure, said means comprising a pressure pump functioning to deliver fuel to the chamber in excess of the delivery capacity of the measuring pump, and a 105 relief valve carried by the fuel chamber and functioning to prevent the pressure developed in said chamber and in the injector line by means of the pressure pump from exceeding a predetermined value.

2. Fuel feeding apparatus for high compression engines comprising a fuel chamber, a measuring pump for delivering fuel from said chamber comprising a cylinder having its inlet connected with said chamber, a plunger operating in said cylinder, a lever operatively connected with said plunger, a cam shaft, a cam on said shaft cooperating with said lever to operate the plunger in one direction, a spring arranged to operate the plunger in the opposite direction, an abutment on said plunger and a tapered member adjustably carried by the reservoir and cooperating with said abutment to regulate the stroke of the plunger under the influence of said spring and 120

means for maintaining a supply of oil in said reservoir.

3. Fuel feeding apparatus as recited in claim 2 in which the last mentioned means comprising a pressure pump including a cylinder having its outlet connected to said fuel chamber, a plunger operating in said cylinder, a spring arranged to operate said plunger on the suction stroke, and a second cam 10 carried by the aforementioned cam shaft and arranged to operate said plunger on the discharge stroke.

4. Fuel feeding apparatus for high compression engines comprising a fuel chamber, a 15 measuring pump for delivering oil from said chamber and a pressure pump for supplying oil to said chamber in excess of the delivery capacity of the measuring pump, each of said pumps including a cylinder having a plunger operating therein, means for placing the fuel chamber in communication with the inlet of the measuring chamber and the outlet of the pressure pump, a single cam shaft, a pair of cams carried thereby, means controlled by 20 one of said cams for operating the plunger of the measuring pump in one direction, means controlled by the remaining cam for operating the plunger of the pressure pump in one direction, and independent means for operating 25 said plungers in the opposite direction.

5. Fuel feeding apparatus for high compression engines comprising a casing formed with an integral fuel chamber located in the upper portion thereof, a measuring pump having its cylinder located in said fuel chamber and communicating therewith, and a plunger 35 operating in said cylinder and projecting below the fuel chamber, a pressure pump including a cylinder located in the casing below the 40 fuel chamber and having its outlet connected

to the latter and a plunger operating in said pressure cylinder and projecting above the same, a cam shaft supported to extend through the casing above the pressure pump, a cam on said shaft engageable with the pressure pump 45 plunger to move the same downwardly, a spring arranged to move the plunger of the pressure pump upwardly when said plunger is free to so move, a lever extending beneath the cam shaft and pivotally mounted at one 50 end and having the other end engaging the plunger of the measuring pump, a second cam on said cam shaft cooperating with said lever to operate the plunger of the measuring pump in one direction, and a spring arranged to operate 55 the plunger of the measuring pump in the opposite direction when the said plunger is free to so move.

6. Fuel feeding apparatus for high compression engines comprising a fuel chamber, a 60 measuring pump including a cylinder arranged in and communicating with said chamber and a plunger operating in said cylinder and projecting beyond the fuel chamber, means for reciprocating said plunger, a collar fixed to the projecting portion of the plunger, a pair of spaced guides carried by and extending circumferentially of the fuel chamber at opposite sides of the projecting portion of said plunger, a longitudinally tapered member carried by and slidably between said guides and formed with a central slot receiving the plunger therethrough, said member being engageable with said collar to regulate 65 the effective delivery stroke of the 70 plunger.

In witness whereof, I have hereunto set my hand.
